TADEUSZ VON RYCHTER, OF WARSAW, RUSSIA.

MACHINE FOR PEGGING SOLES.

1,187,573.

Specification of Letters Patent. Patented June 20, 1916.

Application filed April 7, 1914. Serial No. 830,148.

To all whom it may concern:

Be it known that I, TADEUSZ VON RYCHTER, a subject of the Czar of Russia, and residing at Warsaw, Russia, have invented 5 certain new and useful Improvements in Machines for Pegging Soles, of which the following is a specification.

My invention relates to machines for pegging soles of shoes and the like, and a primary object is to provide an improved machine in which holes are made in the sole by an awl and immediately thereafter pegs cut off from a strip of wood are driven into the holes by means of a hammer, provision 10 being made at the same time by means of a double feed for shifting the sole in the required manner, it being necessary only to press the shoe with the sole to be pegged thereon against the lower part of the machine by hand while the machine is working.

One illustrative embodiment of my invention is represented by way of example in the accompanying drawings, wherein:—

Figure 1 is a front elevation, Fig. 2 a side elevation, partly in section, and Fig. 3 a horizontal section taken on the line A—B in Fig. 2, showing a preferred form of my improved machine; Figs. 4 and 5 are front and side elevations, respectively, showing part of 20 the lower part of the machine on an enlarged scale; Fig. 6 is a side elevation of a part of the feed mechanism, and Fig. 7 is a horizontal section showing the needle guide and the blade which cuts the pegs; Fig. 8 is a diagram showing the arrangement of 25 pegs in the sole, Fig. 9 is an elevation partly in section showing the serrated plates for feeding the sole in their position while the pegs are being knocked in, Fig. 10 is a like 30 view of these plates during the feed of the sole, Fig. 11 is a plan view of the plates, partly in section, and Fig. 12 is a plan view of the guide of the hammer.

Referring to the drawings, a shaft 2 which 35 can be driven either by a motor or by a hand-crank 3 and a flywheel 4 is journaled in the frame 1, and its motion is transmitted by means of two pairs of gear wheels 5, 6 and 5, 7 to two shafts 8 and 9. The shaft 8 40 carries on its front end the driving mechanism for driving the awl for making the holes in the sole, and for the hammer for driving the pegs into the holes. To this end, an anti-friction roller 11 is mounted on a 45 crank 10 fast on the shaft 8. This roller 11 runs in a loop 12 carrying above a prefer-

ably square guide rod 13, guided in the frame 1, and below a rod 14. This rod 14 carries an awl 15 (Figs. 1 and 5) and is guided in a guide 18. In consequence of the arrangement of the roller 11 and the arrangement of the loop 12 the rod 14 is compelled to move vertically up and down. The shaft 8 also carries an eccentric 16 which has on part of its periphery a projecting rim or 60 guide wall 17. An anti-friction roller 19 mounted on a hammer carrier 20 coacts with this guide wall or rim, and a second anti-friction roller 21 likewise carried by the hammer carrier 20 coacts with the periphery 65 of the eccentric. The hammer carrier 20 is guided in suitable manner in the frame of the machine by anti-friction rollers 20^a, 20^b and guide walls 20^c (Figs. 1 and 12), and as clearly shown in Fig. 5 the hammer proper 70 23, which has a slanting face 25 and runs out into a slender portion 24, is pivotally connected to the carrier at 22. When the lower end of the rim 17 coacts with the roller 19, then, as will be seen from Fig. 1, the 75 hammer carrier 20, and the hammer 23 are driven vertically upward until the roller 19 arrives within reach of the circular part of the rim 17. The slanting face 25 of the hammer 23 strikes against the guide 18, and 80 as the hammer 23 is pivoted at 22 it is deflected to the left, as indicated in Fig. 5, and the slender portion 24, which was in alignment with the guide of the awl, is moved out of the path of the awl. At the 85 upper end of the rim 17 the hammer 23 can fall down and is pressed downward by the roller 21 which coacts with the periphery of the eccentric. The pointed portion 24 then enters into the aperture through which the 90 awl has previously passed. The awl and the cutter are influenced in such manner that just when the awl is at its highest point the hammer occupies its lowest position.

As already mentioned, the rotary movement of the shaft 9 is imparted by the pair of gear wheels 5, 7 to the shaft 9. By means of the pinion 26 a gear wheel 27 is rotated by which a pair of bevel-gears 28, 29 is influenced at the same time. The bevel-gear 29 is mounted on a vertical shaft 30 which is journaled in suitable manner and possesses a lug 31 which acts on a ratchet-wheel 32 in such manner that this wheel is moved forward one tooth each revolution of 110 the shaft 30, while a pawl 33 prevents the ratchet-wheel moving too far. The move-

ment of this ratchet-wheel 32 is transmitted by means of a pinion 34 and a spur gear 35 to a toothed feed wheel 36. This feed ratchet-wheel 36 influences the movement of 5 a strip of wood 39 wound up on the drum 37 and sliding in a guide way 38. When the wheel 36 is driven it drives the strip of wood 39 in the guide way 38 into the path of the awl 15. By replacing the wheel 36 by a 10 larger one the speed at which the strip of wood is fed can be increased, so that pegs of various thickness can be cut off in the manner which will now be described.

For the purpose of cutting the strip of 15 wood into pegs a cam 40 is adjustably keyed on the shaft 8 and a cam 41 is mounted in like manner on the eccentric 16. Mounted to rock on the frame of the machine at 20 42 is a lever 43 which coacts in such manner with the cams 40, 41 that one end thereof is tilted to the right by the cam 41 and to the left by the cam 40. The other end of the two-armed lever is connected by means of a pivotal joint to one end of a slide 44 which 25 is driven to and fro by the lever 43 and is provided at its other end with a blade 45. The strip of wood is cut at a suitable moment by the blade 45 and is fed toward the path of the awl by means of the face 46. 30 The individual operations follow one another in such manner that a hole is first made by the awl 15 in the sole 47, and while the awl is moving upward the peg cut off the strip of wood is inserted into the path of 35 the awl and is afterward driven by the point 24 of the hammer into the hole.

As shown in Fig. 8 the pegs are arranged zigzag in the sole. In order to do this in this machine it is necessary for the sole 40 to have imparted to it a twofold movement, *i. e.* a forward movement and a movement at right angles thereto. This is effected by 45 means of the mechanism which will now be described with reference to Figs. 4, 5, 6, 9, 10 and 11. Rigidly attached to the bottom end of the guide 18 for the needle is a roughened or serrated plate 48, against which the sole 47 is pressed by hand, it being secured in position owing to the rough 50 nature of the plate 48. When a peg has been knocked in it is necessary for the sole to be shifted automatically. This is effected by means of a slide 49 which can move to and fro in a guide 50 provided in the frame 55 of the machine. This slide carries a roughened or serrated plate 51 which is so connected with it by means of a lug 52 that it can shift horizontally together with the appertaining parts at right angles to the 60 direction indicated by the arrows A and B shown in Fig. 5, a groove being provided for this purpose in the slide 49, while the slide 49 itself can execute only a reciprocatory motion in the direction of the arrows 65 A and B and the member 51 must partici-

pate in this movement. Fast on the slide 49 is a hook-shaped member 53 whose one end is suspended by means of springs 54 from the frame of the machine. By means of these springs this hook 53 and with it 70 the slide 49 and the serrated plate 51 are held in an elevated position. The said reciprocating motion in the direction of the arrows A and B is brought about by means of an anti-friction roller 58 mounted on a 75 crank 55. The crank 55 is turned by a shaft 56 driven by means of the gear wheels 57, 26 by the pinion 7. In consequence of the shape of the inner wall of the hook 53 the slide 49 is shifted by the roller 58 against 80 the action of the springs 54 in the direction of the arrow A. The slide 49 returns into its original position under the action of the springs 54, this movement being regulatable by the pins 59 which can be inserted more 85 or less in lugs 60 and abut against the fixed faces 61 of the guide, the lugs 60 being rigidly connected with the slide. Owing to the to and fro movement of the slide 49 in the direction of the arrows A and B the 90 serrated plate 51 is compelled to move in the same manner. In addition, as mentioned above, owing to pivot 52 it can move at right angles thereto. This transverse movement is derived from the main shaft 2 by means 95 of a camway 62 which the one end of a two armed lever 63 takes. The other end of this lever is pivotally connected to one end of a slide 64 carrying at its other end a pin 65 which takes into the serrated member 51. 100 In consequence of the cam 62 the slide 64 has imparted to it a reciprocatory motion at right angles to the arrows A and B and drives the serrated member 51 with it in this direction, and the lug 52 slides in a slot 105 in the slide 49. As the member 51 must execute two movements, as already mentioned, the aperture for the pin 65 in the member 51 is made elongated. The serrated member 51 must be firmly pressed against the sole at a suitable moment. This is effected by means of a two-armed lever 66 whose one end carries an anti-friction roller 67 which presses the member 51 downward, 110 while the other end is influenced by a cam 68 fast on the shaft 56.

The described feed mechanism for the sole operates as follows: The sole 47 is firmly pressed against the fixed serrated plate 48 and against a roller 69 mounted on the slide 64, as shown in Fig. 9. As long as the sole is held by hand against the plate 48 it cannot be moved forward. During this time a hole is made in the sole in the manner described above and the peg is then driven by the hammer 23 into the hole. At this moment the awl is located in its highest position and begins to move downward, while the hammer moves upward. The serrated plate 51 is now pressed downward 115 120 125 130

against the sole by the roller 67 under the influence of the cam 68, so that the sole is removed from the plate 48, as shown in Fig. 10. The slide 49 moves in the direction of the arrow A under the simultaneous influence of the roller 58, and therefore drives the sole in the same direction. As the plate 51 is lifted at the same time by the springs 54 the sole again bears firmly against the stationary plate 48, while the slide 49 automatically returns into its original position. By this time the awl has moved downward and the second hole is made. As the holes are to be made zig-zag, as shown in Fig. 8, the plate 51 is simultaneously shifted under the influence of the slide 64 at right angles to the arrow A while the slide 49 and the plate 51 are moved in the direction of this arrow, so that the sole moves in a direction resulting from both these movements and consequently the awl makes holes staggered in the sole. It follows from the above that it is only necessary to tend to press the sole 47 constantly against the plate 48, whereby the sole is automatically guided in a zig-zag line by the plate 51. In consequence of the provision of the roller 69 all the holes are made at predetermined distances from the edge of the sole.

I claim:

1. In a machine for pegging soles, the combination with a frame, of a main shaft journaled therein, an awl movable vertically in the frame and adapted to make holes in a sole pressed against the frame, means driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer for driving a peg into said hole, a cam driven by said shaft for positively lifting said hammer, said hammer being freed from said cam after the lifting thereof, to fall freely, and means driving the hammer downward during the falling movement thereof, and feed mechanism driven by said shaft for automatically feeding the sole.

2. In a machine for pegging soles, the combination with a frame, of a main shaft journaled therein, an awl movable vertically in the frame and adapted to make holes in a sole pressed against the frame, means driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer carrier, a hammer

carried by the carrier for driving a peg into said hole, a cam having a laterally projecting rim at a portion of the periphery thereof driven by said shaft, said hammer carrier carrying a roller adapted to be lifted by said rim and a second roller adapted to be driven by the periphery of the cam, and feed mechanism driven by said shaft for automatically feeding the sole.

3. In a machine for pegging soles, the combination with a frame, of a main shaft journaled therein, an awl movable vertically in the frame and adapted to make holes in a sole pressed against the frame, means driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer carrier, a hammer pivotally carried by the carrier for driving a peg into said hole, cam means driven by the shaft for positively lifting said hammer and driving the same downward, said hammer having a slanting face adapted to coact during its upward movement with the frame and thereby to be rocked out of its normal position, said hammer being freed from said cam after the lifting thereof, to fall freely, and means driving the hammer downward during the falling movement thereof, and feed mechanism driven by said shaft for automatically feeding the sole.

4. In a machine for pegging soles, the combination with a frame, of a main shaft journaled therein, an awl movable vertically in the frame and adapted to make holes in a sole pressed against the frame, a crank driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer for driving a peg into said hole, a cam means driven by said shaft for actuating said hammer, said hammer being freed from said cam after the lifting thereof, to fall freely, and means driving the hammer downward during the falling movement thereof, said crank and said cam means being in their outer end positions at the same time, whereby the awl and hammer are simultaneously moved in opposite directions, and feed mechanism driven by said shaft for automatically feeding the sole.

5. In a machine for pegging soles, the combination of a frame having a roughened plate for steadyng a sole, a main shaft journaled in the frame, an awl movable vertically in the frame and adapted to make holes in a sole pressed against said plate,

- means driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer for driving a peg into said hole, means driven by said shaft for actuating said hammer, and feed mechanism comprising a serrated plate driven by said shaft for automatically removing a sole from said roughened plate and feeding it diagonally forward. 5

6. In a machine for pegging soles, the combination of a frame having a roughened plate for steadyng a sole, a main shaft journaled in the frame, an awl movable vertically in the frame and adapted to make holes in a sole pressed against said plate, means driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer for driving a peg into said hole, means driven by said shaft for actuating said hammer, and elastically suspended feed mechanism comprising two operatively connected slides movable horizontally at right angles to one another, and a serrated plate normally embracing said roughened plate carried by one of the slides, a hook carried by the other slide, a crank-arm, carrying a roller, rotatable in said hook and adapted to be driven by said shaft and to be driven in one direction, and means driven by the shaft for driving the serrated plate in a direction at right angles to the direction of motion of said hook. 15 75

7. In a machine for pegging soles, the combination of a frame having a roughened plate for steadyng a sole, a main shaft journaled in the frame, an awl movable vertically in the frame and adapted to make holes in a sole pressed against said plate, means driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer for driving a peg into said hole, means driven by said shaft for actuating said hammer, and elastically suspended feed mechanism comprising a serrated plate driven by said shaft for automatically removing a sole from said roughened plate and feeding it diagonally forward. 20 25 30

8. In a machine for pegging soles, the combination of a frame having a roughened plate for steadyng a sole, a main shaft journaled in the frame, an awl movable vertically in the frame and adapted to make holes in a sole pressed against said plate, means driven by said shaft for reciprocating said awl, feed mechanism driven by said shaft for feeding a strip of wood to a position above a hole made in the sole by said awl, a blade for cutting a peg off the strip of wood above the hole in the sole, means driven by said shaft for actuating said blade, a hammer for driving a peg into said hole, means driven by said shaft for actuating said hammer, and elastically suspended feed mechanism comprising two operatively connected slides movable horizontally at right angles to one another, and a serrated plate normally embracing said roughened plate carried by one of the slides, a hook carried by the other slide, a crank-arm, carrying a roller, rotatable in said hook and adapted to be driven by said shaft and to be driven in one direction, a cam on said shaft, and means driven by said cam for driving the serrated plate in a direction at right angles to the direction of motion of said hook. 35 40 45 50 55 60 65 70 75 80 85 90 95 100 105 110 115

In testimony, that I claim the foregoing as my invention, I have signed my name in presence of two subscribing witnesses.
